UNITED STATES PATENT OFFICE.

JOB HUTCHINSON, OF BROOKLYN, NEW YORK.

REVOLVING-CYLINDER INTERNAL-COMBUSTION MOTOR.

1,321,046.

Specification of Letters Patent.

Patented Nov. 4, 1919.

Application filed August 21, 1917. Serial No. 187,434.

To all whom it may concern:

Be it known that I, JOB HUTCHINSON, a citizen of the United States, residing at Brooklyn, in the county of Kings and State 5 of New York, have invented new and useful Improvements in Revolving-Cylinder Internal-Combustion Motors, of which the following is a specification.

My invention relates to internal combustion motors, and particularly to that type 10 known as revolving cylinder motors in which a plurality of cylinders are mounted for common revoluble movement.

The objects of the invention are to utilize 15 the principle of my new two-cycle motor, fully described in my application for patent S. No. 183,229, filed July 28, 1917, in the construction of a revolving cylinder motor having none of the objectionable features 20 of this type of motor heretofore produced; to eliminate many of the structural complications of the present motor plants; to provide a motor which has no water cooling apparatus, no crank shaft, no timing 25 gears, and no exhaust and intake manifolds in the generally understood meaning of these terms. Further, to provide a revolving cylinder motor having a plurality of cylinders and operating on the two-cycle principle 30 in which an impulse occurs at each reciprocation of the piston; in which the cylinders are cooled partly by the radiation of heat from the outer surfaces to the surrounding air, and partly by fresh air supplied 35 under pressure to the combustion chamber of each cylinder at the end of the forward stroke of the piston for the purpose of scavenging and aiding in the cooling of the cylinder; in which there are no valves 40 to be operated, and consequently no cams or cam shafts are necessary; and in which the motor as a whole with the accessory parts is mounted in a compact and efficient organization the various parts of which are 45 readily accessible for the purpose of adjustment and for repairs to and replacement of parts.

With these and other objects which will 50 more fully hereinafter appear, the invention consists in the novel construction and arrangement and combination of parts of an internal combustion motor hereinafter

described and claimed, and illustrated in the accompanying drawings, in which drawings—

Figure 1 is a central vertical section 55 through the motor, the piston in one of the cylinders being shown in section while the piston in the other cylinder is shown in elevation;

Fig. 1^a shows the forward part of the 60 motor base with the apparatus mounted thereon;

Fig. 2 is a view in end elevation looking 65 in the direction of the arrow Fig. 1.

Fig. 3 is a top plan view of the motor 70 shown in Figs. 1 and 2.

Referring to the drawings, 1 is the base 75 of the motor upon which all of the parts are mounted and carried. Upon this base is mounted the oil case casting 2 which is bolted to the base by bolts 3 or secured in place in any other suitable manner. This oil case casting has preferably an oblique connection 4 with shell 5 which is securely 75 mounted thereon in any suitable manner and within which is designed to rotate the element carrying the revolving cylinders.

The revolving element comprises a preferably circular casting block 6, formed with 80 chambers 7 which constitute the cylinders of the motor or the greater portion thereof. The outer periphery of the lower end of casting block 6 is provided with packing 85 rings 8 to prevent the oil within the oil case from splashing out.

The motor units upon the revoluble casting blocks are those disclosed in my pending application S. No. 183,229, filed July 28, 1917, 90 where the construction is fully described. This construction will however be briefly described here for a better understanding of the combination as a whole. The units being all alike, a description of one will suffice for all. The chamber 7 is provided with 95 a cylinder lining sleeve 9 which snugly fits the chamber and extends thereabove. A detachable head 10 provided with heat radiating fins fits over the projecting end of sleeve 9 and both are secured to the casting block 100 6 by means of bolt 11.

Within the cylinder thus constituted is located a hollow piston 12 which is of sufficient capacity to provide space for a fixed abut-

ment 13 therewithin, this abutment being anchored to the casting by pin 14. This fixed abutment 13 is hollow and constitutes an initial air compression chamber which 5 communicates by a port 15 having a check valve 16 with the confined space 17 below the abutment which constitutes the initial air compressing chamber. Above the abutment within the hollow piston is the initial 10 charge compression chamber 18. The casting block 6 is formed with suitable inlet and exhaust conduits, these comprising a charge inlet conduit 19 which communicates with annular charge chamber 20 to which the 15 charge is admitted through connection 21. Conduit 22 connects the initial charge compression chamber with the combustion chamber above the piston, and conduit 23 connects the air compression chamber within 20 the hollow abutment with the combustion chamber. These connections are controlled by the various ports in the cylinder wall and in the air compression chamber, as will be described. Conduit 24 admits outside air 25 through conduit 25 to the initial air compressing chamber 17. The cycle of operation of each of the motor units may be briefly stated as follows:

When the piston is in the position indicated at the right in Fig. 1, that is in its outward position, the combustion chamber is exhausting through exhaust ports 26, and outside air is being admitted to initial compression chamber 17. As the piston starts 30 upon its inward stroke the air inlet port of chamber 17 is closed and air is compressed in the air compression chamber within the hollow fixed abutment 13. The charge which had upon the downward stroke been compressed 35 in chamber 18 is admitted through conduit 22 to the combustion chamber, and compression of the charge begins within the combustion chamber. When the piston reaches its inward position, air is fully compressed 40 within chamber 13, and is there confined by a valve 16. Port 27 of the piston then registers with charge conduit 19 and a fresh charge is admitted to initial charge compression chamber 18. The charge in the 45 combustion chamber is then fired, and the piston starts upon its outward movement, during which the new charge is compressed within chamber 18. As the piston again nears the outward end of its stroke exhaust 50 port 26 is uncovered, and piston port 28 connects the air compression chamber 13 with conduit 23, thereby admitting the compressed air to the combustion chamber for the purpose of scavenging. The cycle of 55 operation is then complete.

The casting block 6 is also formed with a central conduit 29 which communicates with the exhaust ports of the cylinders, and is in communication with the hollow shaft 30 60 upon which the casting block is mounted,

and which communicates with the exhaust connection 31. In alignment with the hollow shaft 30 is shaft 32 extending upwardly from the casting block and journaled preferably by means of ball bearings 33 in a bracket 70 34 mounted upon an upright plate 35 secured upon the base 1. The hollow shaft 30 is also preferably provided with ball bearings 36.

Coöperating with the pistons of the motor elements or units, I provide an abutment 37 which is shown as a ring or flange extending around the interior of the shell 5 and securely fastened thereto. This abutment constitutes an important feature of the invention, and is inclined obliquely at an angle to the axis of rotation of the revoluble casting block 6, and is shown extending inwardly from the shell so as to be engaged by the pistons of each of the motor units. This 80 engagement or connection is preferably effected by means of a ball and socket joint so that the connection is a sliding one and yet permits a change in angular relation as each piston moves around within the ring. 90 For this purpose a ball 38 is mounted within a socket 39, the ball having a slot for engagement with the flange or ring 37, and the socket having a sufficiently wide notch to admit said ring in the various positions of 95 the piston. The arrangement is such that under the work impulse of each piston, which occurs after the piston has passed the point of closest proximity of the abutment ring to the cylinder, the piston travels down 100 the slope of the abutment ring and hence forces the revoluble structure to rotate. When the piston reaches the limit of its outward stroke, as shown at the right of Fig. 1, the cylinder exhausts as above described and 105 further rotation causes the movement of the sliding connection up the incline of the fixed abutment and hence the inward movement of the piston to compress the new charge 110 within the combustion chamber.

In the embodiment of the invention as illustrated, I have shown a six-cylinder motor in which there are always two or three of the units acting to cause rotation, this being equivalent to a twelve-cylinder four-cycle motor. It will be understood however that a greater or less number of cylinders may be employed if desired.

The cylinders may be fired in any suitable manner, such as by means of contacts 40 connected to the respective spark plugs and mounted upon a ring 41 carried by the bracket arm 34. A contact brush 42 supplies the ignition current.

Power is transmitted from hollow shaft 125 30 to shaft 43 carrying fly-wheel 44, by means of a bevel gear 45 meshing with bevel pinion 46. Bevel gear 45 also meshes with pinion 47 mounted upon shaft 48 which drives the usual generator 49 and magneto 130

50 by the sprockets located within the casting 51. These parts are mounted upon the forward extension 52 of the base 1, and upon this extension is also mounted a starting motor 53 which is adapted to drive shaft 48 through gears 54 and 55.

In the above construction it will be observed that the intake for the charge through connection 21 and annular chamber 20 is 10 warmed by the exhaust gases passing down through central channel 29 and the hollow shaft 30, thereby promoting combustion of the charge. Also, the intake of air for the carburetor may be passed through chamber 15 56 by connections not shown, so that heavier oils than gasoline such as kerosene may be employed.

It will also be observed that by the above described construction a very smooth running motor is provided, and one in which vibration is reduced to a minimum. When used as an automobile motor the shaft 43 will be connected to the clutch as usual, and all of the parts will be found readily accessible to the operator. The detachable heads 10 of the cylinders may be readily removed, and by removing the bracket 34 the whole motor structure may be taken off leaving the pistons in place. If the inclined abutment 30 ring 37 be released by removing its attaching bolts, the pistons also may be taken out with the motor structure, or they may be removed singly from the ring after the rest of the motor structure has been removed.

35 While I have described an embodiment of my invention which I now believe best for carrying the same into effect, this disclosure is to be taken as merely illustrative and not in a limiting sense, as many changes and 40 modifications may be made in the various details without departing from the scope of the invention as defined in the appended claims.

What I claim as new and desire to secure by Letters Patent of the United States is:—

45 1. A motor including a base, a rotatable block mounted to turn about a vertical axis on said base, a plurality of cylinder and piston units therein, a shell fitted to said base and having its upper end overlapping the lower edge of the superposed casting block, an inclined abutment ring carried by said shell, and means for slidably connecting the piston elements of said cylinder and piston units with the abutment ring.

55 2. A revolving cylinder motor comprising a base, a plurality of cylinders mounted thereon for common revoluble movement and disposed parallel to the axis of revolution, elongated pistons for said cylinders extending outside of said cylinders, an abutment ring fixed with respect to said base and substantially encircling said cylinders and inclined with respect to the axis of revolution for co-operation with said pistons, and a sliding connection between each of said pis-

ton ends and said abutment which comprises a slotted ball engaging said abutment ring and seated within a socket upon the piston.

3. A revolving cylinder motor comprising a base, a casting block rotatably mounted 70 about a vertical axis on said base and having a plurality of cylinder chambers, a sleeve fitted in each chamber, a detachable head co-operating with each sleeve to provide a complete cylinder, a piston in each sleeve, a 75 fixed abutment ring inclined with respect to the said axis of the block, and a self-adjusting member carried by the lower end of each piston and slidably embracing one edge and the upper and lower faces of the ring. 80

4. A revolving cylinder motor comprising a base including an abutment ring inclined with respect to the axis thereof, a cylinder block rotatably mounted about a vertical axis on said base and having a plurality of 85 concentric centrally arranged exhaust, gas, and air passages and also a plurality of vertically disposed cylinder chambers in ported communication with said passages, a plurality of reciprocating piston elements in said 90 chambers, and a self-adjusting member carried by the lower end of each piston and slidably embracing the said abutment ring.

5. A revolving cylinder motor comprising a base including an interior abutment ring 95 inclined with respect to the horizontal plane of the base, a casting block rotatably supported on said base over said ring and forming a housing therefor, a plurality of vertically reciprocating cylinder elements arranged in said block, and a ball and socket device carried by the lower end of each piston for slidably engaging said ring. 100

6. A revolving cylinder motor comprising a base including an inclined abutment ring, 105 a horizontally disposed shaft journaled in said base, gears carried thereby, a casting block rotatably supported on side base over the ring and having a central exhaust chamber, a plurality of reciprocating piston elements in said block and slidably engaging said abutment ring, a hollow vertical shaft journaled in said base and having its upper end engaging with said block and communicating with the exhaust chamber, and a gear 115 carried by the lower end of said shaft and engaging with the gears of said horizontal shaft.

7. A revolving cylinder motor comprising a base, a plurality of vertically disposed two-cycle motor units having cylinders mounted on said base for common revoluble movement and disposed parallel to the axis of revolution at equal distances from said axis, a fixed abutment ring mounted upon said 125 base and having an engagement surface oblique to said axis of revolution and disposed to be engaged by said pistons, a sliding connection between each of said pistons and said surface of said abutment ring, 130

means for admitting a charge for compression within each cylinder as the engagement between its piston and said ring proceeds upwardly to cause the inward movement of the piston, and means for firing the charge after the engagement of each piston with said ring passes the point of greatest inward movement for the piston.

8. A revolving cylinder motor comprising a base, a plurality of cylinders mounted thereon for common revoluble movement and disposed parallel to the axis of revolution, pistons for said cylinders, a fixed abutment ring inclined with respect to the axis of revolution for coöperation with said pistons, and a sliding connection between each of said pistons and said abutment, said base having a forward extension for the mounting of auxiliary apparatus including a motor and 20 a generator.

9. A revolving cylinder motor comprising a base, a casting block formed with a plurality of cylinder chambers and coöperating inlet and exhaust conduits, a shaft upon which said casting block is revolvably 25 mounted upon said base, pistons or cylinders, an inclined fixed abutment for coöperation with said pistons, a sliding connection between each of said pistons and said abutment, a drive shaft for transmitting the 30 movement of said casting block to a device to be driven, a shaft for communicating said movement also to auxiliary apparatus including a generator, and a gearing connection between said casting block and said 35 shafts.

In testimony whereof I have hereunto set my hand.

JOB HUTCHINSON.
